Primary Examiner — Vy N Koenig*Assistant Examiner* — Michelle M Reeves(74) Attorney, Agent, or Firm — Timothy W. Menasco, Esq.; Harter Secrest & Emery LLP(57) CLAIM

The ornamental design of a bench, as shown and described.

DESCRIPTION

FIG. 1 is a top perspective view of a bench in accordance with the present invention;

FIG. 2 is a front side view thereof, a rear side view being a mirror image thereof;

FIG. 3 is a right side view thereof, a left side view being a mirror image thereof;

FIG. 4 is a top view thereof;

FIG. 5 is a bottom view thereof; and,

FIG. 6 is a bottom perspective view thereof.

The broken lines of the Figures depict portions of the bench that form no part of the claimed design.
